UNITED STATES PATENT OFFICE.

WILLIAM P. STARR, OF PHILADELPHIA, PENNSYLVANIA.

SELF-CHARGING SIPHON.

1,195,864.

Specification of Letters Patent. Patented Aug. 22, 1916.

Application filed July 11, 1914. Serial No. 850,855.

To all whom it may concern:

Be it known that I, WILLIAM P. STARR, a citizen of the United States, residing at Philadelphia, in the county of Philadelphia and State of Pennsylvania, have invented 5 new and useful Improvements in Self-Charging Siphons, of which the following is a specification.

The invention relates to siphons, and more 10 particularly to the class of self-charging siphons.

The primary object of the invention is the provision of a device of this character wherein liquids can be transferred from one 15 vessel to another, or the heavier liquid can be separated from the lighter liquid, or vice versa, without disturbing or mixing the same, or stirring up dregs if present therein, the device being especially useful for house- 20 hold purposes, yet it may be used in laboratories, stores, or in fact anywhere where a siphon is used.

Another object of the invention is the provision of a siphon of this character which is 25 novel in form, positive in operation, and durable.

A still further object of the invention is the provision of a siphon of this character which is simple in construction, light in 30 weight, yet strong, and one which can be manufactured at a minimum expense.

With these and other objects in view, the invention consists in the construction, combination and arrangement of parts as will be 35 hereinafter fully described, illustrated in the accompanying drawing, and pointed out in the claim hereunto appended.

In the drawing:—Figure 1 is a side elevation of a bottle or receptacle showing the 40 siphon constructed in accordance with the invention applied. Fig. 2 is a fragmentary vertical sectional view through the siphon.

Similar reference characters indicate corresponding parts throughout the several 45 views in the drawing.

Referring to the drawing in detail, A designates a milk bottle which is of the ordinary well-known construction for containing 50 milk and cream, the latter adapted to be drawn off by the use of the siphon herein-after fully described.

The siphon comprises a substantially U-shaped tube B, which when in use is inverted and has its shorter end 10 inserted

through the mouth of the bottle A substantially the depth of the cream contained therein, while the longer end 11 is exterior of the bottle and is formed with a branch nipple 12 which is angularly disposed with respect to the longer end 11 of the tube B 60 to present a substantially Y-shaped terminal portion, and to this nipple 12 is connected a compressible bulb 13, while fitted on the extremity of the longer end 11 of the tube B is a cup having its bottom wall formed into 65 a flexible flap valve 15 which is adapted to close the extremity of the longer end of the tube 11 on the production of suction therein under the action of the bulb 13.

The device is for general household use in 70 separating the cream from the top of a bottle of milk, or for transferring vinegar from one vessel to another without stirring up the dregs or other foreign matter present therein. However, it is to be understood that the 75 siphon can be used for any purpose required of an ordinary siphon.

To use the siphon it is held by the Y-shaped end between the two fingers of the right hand, the bulb 13 is pressed with the 80 thumb, thus expelling the air from the bulb, and thereafter the other end of the said tube is inserted in the bottle of milk to the depth that it is desired to remove the cream, the thumb then being removed from the bulb, 85 which resumes its original shape, producing a suction causing the closing of the valve 15. The cream, during the expansion of the bulb, is thus drawn into the tube B until it reaches the nipple 12, then by the weight of the 90 cream and atmospheric pressure the valve 15 opens and the cream is discharged and continues to flow from the tube as long as the short end of the tube is immersed and kept 95 higher than the valve 15 at the outer end thereof. It is of course to be understood that the nipple 12 must be at a greater distance from the top of the siphon than the open end of the tube, and that the bulb should have the same cubical area as the 100 portion of the siphon from the inner end of the nipple 12 to the open end of the shorter leg portion 10 thereof. In this way the liquid will be prevented from entering the bulb, which is desirable, owing to the difficulty of thoroughly cleaning the inside of 105 the bulb.

From the foregoing it is thought that the

construction and manner of operation of the device will be clearly understood, and therefore a more extended explanation has been omitted.

5. What is claimed is:—

In combination with a siphon, a cylindrical cup completely closing the end of the longest limb of the siphon, said cup having

the major portion of its bottom wall separated from the body of the cup.

In testimony whereof I affix my signature in presence of two witnesses.

WILLIAM P. STARR.
